GEORGE WILBUR GWINN, OF HEWLETT, NEW YORK, ASSIGNOR TO AMERICAN MACHINE & FOUNDRY COMPANY, A CORPORATION OF NEW JERSEY.

METHOD OF MAKING CONTAINERS FOR CAKES, ETC.

Application filed May 2, 1927. Serial No. 188,087.

This invention relates to an improved method of making containers for cakes or similar soft food products, its main object being to provide a hermetically sealed container for soft articles which cannot be handled or subjected to pressure while being wrapped. Such containers heretofore have been made with an inserted flange to which the cover is sealed, and with a body having a series of overlaps or pleats more or less haphazard in arrangement. The present improvement controls the number and shape of such pleats, so that the package can be made geometrically symmetrical and uniform and will present a better appearance.

This is accomplished by providing the shaping dies with slots in a suitable arrangement to guide the wrapper when being formed into shape to receive the cake. By varying the arrangement of slots and the kind of relative motion between the top and bottom dies, any number and shape of overlaps or pleats within the limits of the container may be formed. Thus, by using a slotted bottom die, a vertically sliding top die, and a system of hinged pressure fingers surrounding both dies when forced together, a box-pleated container of the desired shape and with the desired number of pleats can be produced. Or, by using dies of special shape, the lower portion of the side walls of the container may be made in corrugated form, while the top portions are box-pleated. In square, rectangular or polygonal containers, the pleats are of course placed at the corners. For circular, oval or heart-shaped and other curved forms, the number, shape and disposition of the pleats is arranged to best suit the general appearance of the container.

The cover may be laid on and sealed after the flange is made, or it may be attached to the flange during formation of the latter. In the latter case, the article to be wrapped must of course be inserted in the container directly after forming its body portion; but the cover, being sealed by the same formation that produces the flange, can then also be made with box-pleats corresponding to those of the container.

The side walls of the container may be made sloping, so that a number of containers may be nested together if desired.

In the accompanying drawings, in which like characters of reference indicate the same

or like parts, Figs. 1 and 1^a to 4 and 4^a illustrate successive stages in producing a box-pleated container with a sealing flange; Figs. 5 and 5^a illustrate a rectangular container with box-pleats at the corners; Fig. 6 shows the same container after its flange has been inverted; Fig. 7 shows a circular or oval container with box-pleats; Fig. 8 shows a box-pleated circular or oval container with its flange inverted and its cover sealed; and Fig. 9 shows a circular or oval container with the cover in process of being sealed, the lower portion of the side walls in this case being corrugated, while the upper portion is box-pleated.

Referring to Fig. 1, which is a top view, and Fig. 1^a which is a sectional side elevation, 10 indicates a sheet of wrapping material of the proper shape which is to be made into a container. It is placed upon the bottom die 11, provided with slots 12, and is then forced downwardly by the top die 13. As the die 13 sinks into the die 11, or as either, in this or reversed position, is moved towards the other, thereby forming the cup-like depression by folding up the edges of the wrapper, the surplus material emerges from the slots 12 and forms the loops 14 shown in Figs. 2 and 2^a. When the top die has been completely compressed, the hinged Fingers 15 are closed around the bottom die, thereby flattening out the loops and forming the box-pleats 16, as shown in Figs. 3 and 3^a. The top edge of the container thus formed is then turned outwardly as by the cover die 17, shown in Figs. 4 and 4^a, thereby forming the sealing flange 18.

After the article has placed in the container, and while the latter is still held in the bottom die 11, a cover sheet of the proper shape is pressed on to the flange 18, as by a suitable die, either before or after the flange has been inverted or turned down parallel with the sides of the container. When the cover is applied to the sealing flange, while the latter is in the horizontal position shown in Figs. 4 and 4^a, the cover and flange are simultaneously turned downwardly, and the flange turning die may be so arranged that the cover is box-pleated around the box pleats of the flange, thereby producing an interlocked seal which is held in place by applying paste to one of the joined surfaces; or, in case of waxed paper, by subsequent heating of the joint.

In Figs. 5 and 5^a are shown respectively the top view and side elevation of a rectangular container 19, produced by the method shown in Figs. 1 and 1^a to 4 and 4^a, the box-
5 pleats 16 in this case being located at the corners and folded equally over the two adjoining sides of the box. When inverting the flange 18, the pleats are neatly folded under, giving to the box the form shown in
10 Fig. 6.

Fig. 7 shows a circular or oval container 20 made by the improved method, the box-
15 pleats 16 being symmetrically arranged around the curved surface. In Fig. 8, the same container 20 is shown sealed by a cover 21, the box pleats of the latter interlocking with those of the former.

In Fig. 9, a container 22 with a cover 23 is shown, the dies for forming the same being
20 made of such form as to produce the corrugations 24 along a portion of its height, and the box-pleats 25 along the remainder. The cover 23, which is shown partly inverted, has the corrugations 26 arranged to match the
25 box-pleats 25 and covering the latter when completely turned down and folded on the flange 18 of the container 22. The container 22 is made with slightly sloping side walls suitable for nesting.

30 According to the shape of the dies and to the number and arrangement of the slots, containers of many shapes and with many arrangements of box-pleats—with or without corrugations—may be produced by this
35 method.

What is claimed is:

1. The method of making a package, which consists in folding a sheet of paper to
40 form a container bottom having an upstanding wall provided with a series of outstanding loops, then forming said loops into box-

pleats on said wall, then folding the upper part of said wall outwardly to form a flange, then filling the container so formed, then attaching a cover to said flange, and then
45 folding said cover and flange down together on said wall.

2. The series of steps in a method of making a package, which consists in folding a sheet of paper to form a container bottom 50 having an upstanding wall provided with a series of outstanding loops, then forming said loops into box-pleats on said wall, then folding the upper part of said wall outwardly to form a flange, then filling the container so formed and then attaching a cover
55 to said flange.

3. The series of steps in a method of making a container, which consists in folding a sheet of paper to form a container bottom 60 having an upstanding wall provided with a series of outstanding loops, then forming said loops into box-pleats on said wall, and then folding the upper part of said wall outwardly to form a flange.
65

4. The series of steps in a method of making a container, which consists in folding a sheet of paper to form a container bottom having an upstanding wall provided with a series of outstanding loops, and then forming said loops into box-pleats on said wall.
70

5. The method of making a container, which consists in folding a sheet of paper to form a container bottom having an upstanding wall provided with a series of outstanding loops, then forming said loops into box-
75 pleats on said wall, and then doubling the upper part of said wall back on itself.

In testimony whereof, I have signed my name to this specification.

GEORGE WILBUR GWINN.
